UNITED STATES PATENT OFFICE.

RUDOLPH E. BRUCKNER, OF MOUNT VERNON, NEW YORK, ASSIGNOR TO COMMERCIAL ACETYLENE COMPANY, OF NEW YORK, N. Y., A CORPORATION OF NEW JERSEY.

SAFETY CUT-OFF FOR STORAGE LIGHTING SYSTEMS.

No. 869,878.

Specification of Letters Patent.

Patented Nov. 5, 1907.

Application filed April 29, 1907. Serial No. 370,796.

To all whom it may concern:

Be it known that I, RUDOLPH E. BRÜCKNER, a citizen of the United States, residing at Mount Vernon, Westchester county, New York, have invented certain new and useful Improvements in Safety Cut-Offs for Storage Lighting Systems, of which the following is a full, clear, and exact description.

My invention relates to improvements in safety cut-off apparatus for gas lighting systems, the idea being 10 to prevent the escape of gas from the storage reservoir in the event of the high or low pressure system being broken as a result of accident.

The object of the invention is to provide a simple and effective means for positively accomplishing this result, 15 which shall be so located as to prevent its being tampered with.

In the accompanying drawings—Figure 1 is a conventional illustration of a gas lighting system, including a storage reservoir, a regulator and a pipe leading to 20 and from the latter; Fig. 2 is a relatively enlarged view, partly in section, of the cut-off for the high pressure line, together with associated parts; Fig. 3 is a cross section of the low pressure cut-off, said view being in section and showing other associated parts.

25 1 is the main storage cylinder or tank, containing gas. 2 is a valve for the outlet from said cylinder.

3 is the high pressure line extending from the cylinder 1 to a pressure regulator 4, of any suitable construction.

30 5 is a low pressure line leading from the regulator 4 to the burners.

6 is a strainer within the storage tank 1, and protecting the outlet.

7 is a ball valve which is slightly smaller in size than 35 the bore 8, in which it stands. This bore 8 is formed in the body of the valve casing between the interior of the cylinder 1 and the valve 2.

9 is a spring serving to keep the ball 7 normally unseated.

40 10 is the seat for the ball valve 7.

11 is the stem by which the valve 2 is operated.

12 is a pin projecting from the forward end of the valve 2 toward the ball valve 7. When the valve 2 is seated, the pin 12 will impinge against the ball valve

45 7 and unseat the same.

Assuming the high pressure line 3 is broken, the quick escape of gas will cause the ball 7 to move against its seat 10, so as to positively close the outlet from cylinder 1. To insure this action, it is preferable that the 50 area of the space around the ball in the bore 8 be less than the area of the space around the pin 12 forward of the seat for the valve 2. By this construction, the pressure beyond the valve 7 quickly dropping, the said valve 7 is bound to be forced against its seat so as to

effectively close the outlet and prevent the escape of any gas. When the high pressure line 3 is repaired, the valve 11 may be screwed down so as to first unseat the ball valve 7, whereupon an equilibrium will be established on opposite sides of the ball, so that upon again opening valve 2, gas will flow through the high pressure line 3 to the regulator. Where a regulator is used, the usual low pressure line 5 extends beyond the same. Should a break occur in said low pressure line, it is obvious that the regulator 4 would not permit the escape of gas fast enough to operate the valve 7 with certainty. To that end, therefore, I provide a second automatic valve, as best seen in Fig. 3. This valve is indicated at 14 and is of the same type as the ball valve 7. This valve is likewise normally held unseated by the spring 15. This spring may be lighter than spring 9.

16 is an automatic valve controlled by the regulating apparatus, which may be of any well-known construction. This valve is located between the valve 14 and the low pressure outlet 5. In other words, this valve 75 14 is located on the high pressure side of the regulator. If a break occurs in the low pressure line 5, the valve 16 will open wide, momentarily permitting an abnormal outward flow of gas past valve 14. This will cause the ball 14 to move to the right, as viewed in Fig. 3, until it is firmly seated to prevent the further escape of gas. In this instance I provide no means to unseat valve 14, and this is preferable in the construction shown.

In the event of a break and the closing of valve 14 when the repair is effected, the coupling between the high pressure line 3 and the regulator may be broken after first closing valve 2. Valve 14 will then be unseated by spring 15. On recoupling the system and opening valve 2, normal conditions will be obtained. In this case the passage beyond the valve 14 should be 90 of greater cross-sectional area than the passage around the valve. In this respect both safety valves are of similar arrangement.

17 is a felt washer which may be provided to filter the gas.

95 18 is a pressure-controlled diaphragm, by which the valve 16 is operated through bell-crank 19.

A detail description of the regulating apparatus of the type illustrated may be found in Patent No. 788,240.

100 What I claim is—

1. A safety cut-off for gas storing and lighting systems, comprising a storage reservoir, an outlet pipe, a manually operable valve therefor, a separate check valve between the manually operable valve and the interior of said reservoir, means for normally holding said check valve open, and means carried by the first-mentioned valve for unseating the second-mentioned valve when the first one is closed.

105 2. A safety cut-off for gas storing and lighting systems,

comprising a storage reservoir, an outlet pipe, a manually operable valve therefor, a separate check valve between the manually operable valve and the interior of said reservoir, a spring for normally holding said check valve open, and a 5 strainer within the storage reservoir and protecting the outlet.

3. In a gas storage and lighting system, a storage reservoir, a pipe line extending therefrom, an automatic regulating apparatus in said pipe line arranged to reduce and 10 maintain with substantial uniformity the pressure in that part of the line beyond said regulating apparatus, a manually operable valve in the pipe line between the reservoir and regulator, and a separate check valve between the reservoir and the manually operable valve, and a second check 15 valve between the manually operable valve and the regulator, and means for holding both of said check valves unseated during the normal operation of the apparatus.
4. In a gas storage and lighting system, a gas storage tank, a pipe line leading therefrom, a regulator in said pipe 20 line and adapted to reduce and maintain at a substantially uniform pressure the gas therein beyond said regulator, a manually operable valve between the storage tank and the regulator, and means separate from said manually oper-

able valve and between the storage tank and said regulator for automatically closing said pipe line in the event of a 25 break beyond said automatic closer.

5. In a gas storage and lighting system, a gas storage tank, a pipe line leading therefrom, a regulator in said pipe line adapted to reduce and maintain at substantial uniformity the pressure therein beyond said regulator, a 30 manually operable valve, and means for automatically closing said pipe line in the event of a break, including two check valves separate from each other and from said first valve.

6. In an apparatus of the character described, a gas storage reservoir, an outlet pipe, a gas pressure reducing device in said outlet pipe, a valve between said reservoir and pressure reducer, and two check valves in said pipe line, one being arranged between the pressure reservoir and the manually operable valve, the other being arranged between the manually operable valve and the pressure reducer. 35 40

RUDOLPH E. BRUCKNER.
